UNITED STATES PATENT OFFICE.

FREDERICK PEITER, OF BROOKLYN, NEW YORK, ASSIGNOR TO ROBERT SAYRE KENT, INC., OF BROOKLYN, NEW YORK, A CORPORATION OF NEW YORK.

KILN.

Application filed December 4, 1919. Serial No. 342,458.

To all whom it may concern:

Be it known that I, FREDERICK PEITER, a citizen of the United States, residing at Brooklyn, in the county of Kings and State 5 of New York, have invented certain new and useful Improvements in Kilns; and I do hereby declare the following to be a full, clear, and exact description of the invention, such as will enable others skilled in the art 10 to which it appertains to make and use the same, reference being had to the accompanying drawings, and to characters of reference marked thereon, which form a part of this specification:

15 The present invention refers, generally, to improvements in drying, revivifying and decarbonizing kilns; and the invention relates, more particularly, to an improved construction of rotary kiln and means for heating the same.

20 The invention has for its principal object to provide in combination with a rotary kiln a novel construction and arrangement of fire box and combustion chamber designed 25 to produce a more even heating of the kiln drum, and to prevent the application of too intense heat against the surface of the kiln drum tending to burn through the shell so as to require frequent and expensive repairs 30 and replacements thereof.

35 Other objects of the present invention, not at this time more particularly enumerated, will be clearly understood from the following detailed description of the same.

The invention is clearly illustrated in the 40 accompanying drawings, in which:

Figure 1 is a longitudinal vertical section of a rotary kiln, made according to and embodying the principles of the present invention, the kiln drum being illustrated in side elevation.

Figure 2 is a vertical cross-section of the same, taken on line 2—2 in said Figure 1, said view being drawn on an enlarged scale.

45 Similar characters of reference are employed in all of the hereinabove described views, to indicate corresponding parts.

50 Revolving of rotary kilns, of the type with which the present invention is concerned, are commonly employed to roast or bake bone-black, fuller's earth and various other substances that require a comparatively moderate heat, generally about 1100 degrees F., distributed in the enclosing chamber in 55 which the kiln drum revolves. These kilns,

as heretofore constructed, have the fire box communicate directly with the enclosing chamber in which the kiln drum is mounted, thus exposing a considerable portion of the surface of the steel shell comprising the kiln 60 drum to the fire so that the major portion of the heat of the fuel bed is directly communicated to said shell by radiation. It therefore follows that the exposed portion of the drum shell is subjected to a more intense 65 heat, at such point, than is desirable for the best treatment of the material to be baked or roasted, and also this intense heat, directly radiated against the exposed portion of the drum shell, has a deleterious effect upon 70 the shell, burning the same through, and thereby rendering expensive repairs and replacements more frequently necessary than is the case with the improved construction of kiln made according to the principles of 75 the present invention.

Referring now to the accompanying drawings, the improved construction of rotary or revolving kiln embodying the principles of my present invention, comprises a suitable 80 housing 1, usually built of brick, the construction of which is reinforced by suitably disposed buckstaves 2. The upper portion of the interior of the housing provides a drum chamber 3, through which extends the 85 kiln drum 4. The kiln drum comprises a cylindrical hollow steel shell, provided at each end with journals 5, which are mounted in bearings 6 carried by suitably arranged brackets 7 connected with the opposite exterior ends of the housing 1. One of said journals 5 is provided with a sprocket wheel 8, or other suitable rotating means through which a rotary impulse may be imparted to the drum by means of transmission mechanism (not shown) driven from any desired 90 source of power.

The axis of the drum is inclined downwardly from its receiving end toward its discharge end, so as to permit a traveling 100 movement through the drum of material delivered thereto for treatment.

In my novel construction and arrangement of kiln, the fire-box 9 is located within the lower part of the housing 1 beneath and 105 adjacent to the discharge end of the drum 4, said fire box containing the fuel supporting grate 10 beneath which is an ash-pit 11. One wall of the housing 1 is provided with openings leading respectively into the fire- 110

box and ash pit, said openings being fitted respectively with the fire-box door 12 and ash pit door 13. Extending forwardly from said fire-box 9 and beneath said drum chamber 3 is a combustion chamber 14, the same being separated from said drum chamber 3 by a transverse arch partition 15. Located at the forward end portion of said housing, beneath the receiving end of said drum 4 is 5 a port 16 which affords communication between the combustion chamber 14 and the forward end of the drum chamber 3. Mounted in connection with said housing 1, and in communication with the rear end of 10 said drum chamber 3 is a flue or stack 17.

In the novel construction and arrangement of kiln as above described, the fuel for generating heat is burned upon the grate 10 within the fire-box 9. From the fire-box 9 20 the products of combustion resulting from the burning fuel pass forwardly through the combustion chamber 14, from thence passing through the port 16 into the drum chamber 3, wherein the same surround the 25 drum 4, passing rearwardly through the combustion chamber 3 to finally escape from the rear end of the latter through the flue or stack 17.

The advantages of the construction and 30 method of heat conduction involved are; first, the shell of the kiln drum is not exposed to the fire, that is to direct radiation of heat from the burning fuel; second, the long combustion chamber through which the 35 products of combustion must pass, before gaining entrance into the kiln chamber 3, assures perfect combustion, allows time for said products of combustion to thoroughly intermingle, thus tending to produce an even 40 temperature; and, third, some heat contacting with the arch or partition passes therethrough and is radiated from the upper surface thereof into the drum chamber to the kiln drum, and is consequently abstracted 45 from the products of combustion before the latter enter through the port 16 into the drum chamber thereby reducing their temperature at the point where they first come in contact with the drum shell, and tending 50 to produce, as they pass through the drum chamber, in combination with the heat radiated through the arch or partition, a more nearly equalized temperature condition 55 throughout the interior of the drum chamber, and a temperature of the desired comparatively low degree.

I am aware that some changes may be made in the construction of kiln above described and as illustrated in the drawings, while still retaining the general principles 60 of my invention. Hence I do not limit my invention to the exact arrangements and construction of parts, as described in the foregoing specification, nor do I confine myself to the exact details of the construction 65 of the various parts as illustrated in the accompanying drawings.

I claim:—

1. In a rotary kiln, a main housing providing a drum chamber in its upper portion, a kiln drum mounted to extend through and rotate in said drum chamber, a fire-box in the lower portion of said housing beneath the discharge end of said kiln drum, a combustion chamber extending forwardly from 75 said fire-box through the lower portion of said housing, a horizontal partition member separating said fire-box and combustion chamber from said drum chamber, said partition member having a port beneath the receiving end of said kiln drum affording communication between the forward ends of 80 said combustion chamber and said drum chamber.

2. In a rotary kiln, a main housing having a longitudinally disposed drum chamber in its upper part, a kiln drum mounted to extend through and rotate in said drum chamber, the receiving end of said kiln drum being disposed at the forward end of said 90 drum chamber and its discharge end at the rearward end of said drum chamber, a stack or flue communicating with the rearward end of said drum chamber, a fire-box in the lower portion of said housing beneath the 95 rearward end of said drum chamber, a combustion chamber extending forwardly and longitudinally from said fire-box through the lower portion of said housing, the forward end of said combustion chamber communicating with the forward end of said 100 drum chamber, and a horizontal partition member arranged within said housing to separate said drum chamber from said fire-box and said combustion chamber.

In testimony that I claim the invention set forth above I have hereunto set my hand this 19th day of November, 1919.

FREDERICK PEITER.
